Primary Examiner—Prabhakar Deshmukh

(74) Attorney, Agent, or Firm—Frederick H. Gribbell

(57) **CLAIM**

The ornamental design for an electronic lock box, as shown and described.

DESCRIPTION

FIG. 1 is a top front and right side perspective view of an electronic lock box with its key compartment door closed, showing our new design.

FIG. 2 is a front, elevational view of the electronic lock box of FIG. 1.

FIG. 3 is a right-hand side, elevational view of the electronic lock box of FIG. 1.

FIG. 4 is a top, plan view of the electronic lock box of FIG. 1.

FIG. 5 is a bottom, plan view of the electronic lock box of FIG. 1.

FIG. 6 is a rear, elevational view of the electronic lock box of FIG. 1; and,

FIG. 7 is a top front and right side perspective view of the electronic lock box of FIG. 1, with its key compartment door open. The left-hand side of the electronic lock box is a mirror image of the right-hand side depicted in FIG. 3.

1 Claim, 6 Drawing Sheets
